CLAIM

The ornamental design for a cutter for an electric shaver, as shown and described.

DESCRIPTION

FIG. 1 is a front elevational view of a cutter for an electric shaver showing my new design; the rear elevational view being a mirror image;

FIG. 2 is a top plan view thereof;

FIG. 3 is a right side elevational view thereof; the left side elevational view being a mirror image; and,

FIG. 4 is a bottom plan view thereof.

The unshaded areas inside the central circular outline in FIG. 2 and central rectangular outline in FIG. 4 form no part of the claimed design.
